UNITED STATES PATENT OFFICE.

LUTHER M. LIGGETT, OF GALION, OHIO.

SPARK AND THROTTLE CONTROL.

Application filed January 8, 1923. Serial No. 611,288.

To all whom it may concern:

Be it known that I, LUTHER M. LIGGETT, a citizen of the United States, residing at Galion, in the county of Crawford and State of Ohio, have invented certain new and useful Improvements in Spark and Throttle Controls, of which the following is a specification.

The present invention relates to a spark and throttle control and has for its object to provide a novel mounting for the throttle and spark levers, whereby a convenient, compact and protected construction is provided.

Further objects of the invention are to provide a device of this character which is comparatively simple and inexpensive in its construction, which provides for an accurate movement of the control levers, which has a compensating connection between the control levers and the respective tubes so that the control levers will still move in the same plane even though the tubes may spring or be thrown slightly out of alinement, and which completely houses and conceals the connections so that proper operation of the device will not be prevented by accumulations of moisture and dirt on the interior thereof.

With the above and other objects in view, the invention consists in certain combinations and arrangements of the parts as will more fully appear as the description proceeds, the novel features thereof being pointed out in the appended claims.

For a full understanding of the invention reference is to be had to the following description and accompanying drawings in which,

Figure 1 is a top plan view of a control device which is constructed in accordance with the invention, the control levers being shown by dotted lines in the positions assumed when swung to opposite limits of their movement.

Figure 2 is a transverse sectional view through the device, said view being taken substantially on the line 2—2 of Figure 3.

Figure 3 is a vertical sectional view through the device, on the line 3—3 of Fig. 2.

Figure 4 is an enlarged fragmentary sectional view taken substantially on the line 4—4 of Figure 1.

Figures 5 and 6 are detail views of one of the spider elements.

Corresponding and like parts are referred

to in the following description and indicated on all of the views of the drawings by like reference characters.

Referring to the drawings, which illustrate one of many possible embodiments of the invention, the numeral 1 designates the base of the control device, said base being formed of hard black fibre, hard rubber or other suitable material, and having a depression 1^a in the bottom thereof which is of a suitable size and depth to receive the usual steering post nut when the base is assembled on the steering wheel. A recess 1^b is formed at the top of the depression 1^a and receives a metal bottom plate 2 which is swaged upon or otherwise securely fastened to the support tube 3.

The top of the base member 1 is formed with an upstanding annular rib 4, and rotatably mounted upon the base member is a ring 5 which carries the throttle lever 6. This ring is provided at the top and bottom thereof with annular grooves 7. The downwardly facing groove 7 of the ring loosely receives the rib 4 of the base 1, while the upwardly facing groove 7 receives the downwardly extending annular rib 8 of the intermediate guide plate 9, said intermediate plate being also formed with a similar upwardly projecting rib 8.

The throttle lever ring 5 is provided upon the inner periphery thereof with a pair of recesses 10 which loosely receive the arms of a spider member 11. The hub portion of the spider member is shown as having the inner periphery thereof serrated so that it can be swaged or forcibly fitted upon the upper end of the throttle tube 12. The free ends of the spider 11 loosely engage the recesses 10 of the ring so that there is in effect a loose or compensating connection between the throttle lever ring and the throttle tube. The throttle lever ring is closely confined between the base 1 and intermediate guide plate 9, and is accurately guided by engagement of the ribs 4 and 8 with the annular groove 7 thereof, so that it always turns in the same plane and has an accurately defined path of movement. This will not be disturbed even though the spider may be canted with respect to the tube or the tube may be somewhat sprung out of alinement.

Arranged above the intermediate guide plate 9 is the spark lever ring 13 which is somewhat similar in construction to the

throttle lever ring 5, being provided with a downwardly facing annular groove 14 which engages the upper rib 8 of the intermediate plate 9. The spark lever 15 is carried by the ring 13 and provides a means for rotating the same. The inner periphery of the spark lever ring 13 is recessed to receive the arms of a spider member 16 which is substantially identical in construction with the spider member 11, having the inner periphery of the hub portion thereof serrated so that it can be swaged or driven tightly upon the upper end of the spark tube 17. The spark lever ring 13 is accurately guided in its movements and turns in a fixed plane, and the spider member 16 provides a loose or compensating connection between the said ring and the spark tube 17, so that the accurate movement of the ring will not be changed even though the spider member may have a canted relation to the tube or the tube may be sprung somewhat out of alignment.

A top plate 18 is arranged above the spark lever ring 13 and engages the top thereof. A pair of tie bolts 19 connect the top plate 18 to the bottom plate 2, extending through suitable openings in the intermediate guide plate 9 and the base 1. The lower ends of the tie bolts 19 are threaded so that they can be screwed directly into the corresponding openings in the bottom plate 2, and nuts 20 which are fitted upon the lower ends of the bolts engage the top of the base 1 so that the said base is clamped between the nuts and the bottom plate. An upper set of nuts 21 are screwed upon the upper extremities of the tie bolts 9, and after the nuts have been properly adjusted a nut lock plate 22 is placed in position. This plate has openings which correspond in size and shape to the polygonal nuts 20 and engage the nuts to prevent rotation thereof.

A cap member 23 which is preferably formed of the same material as the base 1 fits over the top of the control device, having the interior thereof recessed and threaded, as at 24, so that it can be screwed upon the top plate 18. A shoulder 25 then engages the nut lock plate 22 to hold the said plate in position. It will also be noted that an intermediate ring 26 of the same material as the base 1 and cap member 23 surrounds the intermediate guide plate 9 and is interposed between the throttle lever ring 5 and the spark lever ring 13, so that the exterior of the device has a continuous smooth surface.

The top of the cap member 23 is formed with a central opening which receives the stem of a button 27 which is intended to control the electric horn or other signal member with which the vehicle is equipped.

The top of the button is formed with an

over-hanging and downwardly inclined flange 27a which cooperates with an upstanding boss 23a at the top of the cap member to prevent rain or moisture from entering the interior of the device around the sides of the button. The inner end of the button 27 has a plate 28 secured thereto in a suitable manner as by means of the screw 29 and the edges of the plate project beyond the sides of the button and cooperate with an inwardly facing shoulder 30 on the cap member 23 to limit the outward movement of the button. A spring 31 which has the upper end thereof engaged by the screw 29 normally tends to push the button upwardly, although when the button is forcibly moved inwardly against the action of the spring, the head of the screw 29 constitutes a contact member which is brought into engagement with an opposed contact 32 carried by an insulating washer 33 which is applied to the upper end of an electric cable 34. This cable passes through the spark tube 17, and it will be noted that the top plate 18 is formed with a central opening which loosely receives the upper end of the spark tube. The insulating washer 33 has a sufficiently large diameter so that the edge portions thereof extend beyond the spark tube and rest upon the nut lock plate 22. The contact member 32 is thus insulated, while the spring 31 engages some part such as one of the nuts 20, so that it is grounded. It will accordingly be understood that when the button 27 is pressed downwardly and the two contacts brought into engagement, the electric circuit will be closed and the horn or other signal device sounded.

The device will be mounted upon the top of the steering wheel hub and will be arranged in a very convenient position for manipulation by the driver of the vehicle while steering the same. The spark and throttle levers are accurately guided in their movements and the two levers are preferably inclined upwardly on different angles so that the free ends of the levers will be in the same transverse plane, this being preferably a plane corresponding to the top of the steering wheel. This is a feature which will facilitate manipulation of the control members. While the device can be easily taken apart or assembled, the interior parts of the mechanism are completely housed, so that they are protected against accumulations of dirt and moisture.

While one particular embodiment of the invention has been illustrated and described in detail, it will be understood that I do not restrict myself thereto, since many modifications and changes can be made in the details of construction without departing from the spirit of the invention or the scope of the claims.

Having thus described my invention what I claim as new and desire to secure by Letters Patent is,

1. A motor vehicle control including spaced rotary rings having a common axis and provided with independent finger levers, means for guiding the rings in their rotary movements, concentric rotary members at the axis of the rings, and compensating connections between the said concentric rotary members and the respective rings.

2. A motor vehicle control including spaced rings having a common axis and provided with independent finger levers, the inner peripheries of the rings being notched, means for directing the rings in their rotary movements, concentric rotary members at the axis of the rings, and spiders applied to the concentric rotary members and having arms thereof loosely received within the notches of the respective rings.

3. A motor vehicle control including spaced rings having a common axis and provided with independent finger levers, an intermediate plate engaging the rings to guide the same in their rotary movements, concentric members arranged at the axis of the rings, and spiders applied to the respective concentric members and having a compensating engagement with the respective rings.

4. A motor vehicle control including spaced rings having a common axis and provided with independent finger levers, an intermediate plate, base and cap members, connecting means between the base and cap members to hold the parts together, the intermediate plate being provided with means for engaging the rings to guide them in their rotary movements, concentric actuated members at the axis of the rings, and compensating connections between the actuated member and the respective rings.

5. A motor vehicle control including spaced concentric rings provided with independent finger pieces, an intermediate plate between the rings, top and bottom members, connecting means between the top and bottom members, the members in engagement with the rings having a rib and groove connection therewith to direct the rings in their rotary movements, concentric actuated members at the axis of the rings and spiders applied to the respective actuated members

and having the arms thereof in a loose engagement with the respective rings.

6. A motor vehicle control including a rotary member provided with a finger piece, members engaging both faces of the rotary member and cooperating therewith to direct the rotary member in its movements, a fastening element connecting the said members to each other, locking means for the fastening member, a removable cap piece holding the locking member in position, and an actuated member arranged at the axis of the rotary member and operatively connected thereto.

7. A motor vehicle control including a rotary member provided with a finger piece, an actuated tube at the axis of the rotary member and operatively connected therewith, guide means for the rotary member including a cap piece, a button mounted upon the cap piece, a conduit extending through the actuated tube, and opposed contacts operatively connected to the conduit and button.

8. A motor vehicle control including a plurality of spaced superposed rotary members concentrically arranged and having independent finger pieces, guide means for the rotary members, concentric actuated tubes arranged at the axis of the rotary members and operatively connected thereto, a cap piece applied to one of the guide members, a button mounted upon the cap piece and arranged opposite the ends of the concentric actuated tubes, an electric cable extending through the said tubes, and contact means actuated by the button for controlling the electric circuit.

9. A motor vehicle control including a rotary control member provided with a finger piece, guide means engaging the control member to direct the rotary movements thereof and including a threaded plate, a cap member screwed upon the threaded plate, a tubular actuated member arranged at the axis of the control member and operatively connected thereto, an electric cable extending through the tubular member, a button mounted upon the cap member opposite the end of the tubular actuated member, and contact means actuated by the button for controlling the electric circuit.

In testimony whereof I affix my signature.

LUTHER M. LIGGETT.
